UNITED STATES PATENT OFFICE.

JAHN JASUS, OF STREATOR, ILLINOIS.

DESIGN FOR A POCKET-BOX.

48,064.

Specification for Design.

Patented Nov. 2, 1915.

Application filed August 25, 1915. Serial No. 47,338. Term of patent 7 years.

To all whom it may concern:

Be it known that I, JAHN JASUS, a citizen of the United States, residing at Streator, in the county of La Salle and State of Illinois, have invented a new, original, and ornamental Design for a Pocket-Box, of which the following is a specification, reference being had to the accompanying drawing, forming part thereof.

In the drawings: Figure 1 is a front elevation of the device, Fig. 2 is a side elevation thereof, and Fig. 3 is an end elevation of the same.

I claim:—

The ornamental design for a pocket box as shown.

JAHN JASUS.

Witnesses:

JOHN TULEY,

H. W. SEAGER.
